UNITED STATES PATENT OFFICE

159,645

MEMORANDUM CARD AND PENCIL HOLDER

George Knorr, Chicago, Ill., assignor of one-half to Walter Knorr, Chicago, Ill.

Application August 5, 1949, Serial No. 4,316

Term of patent 14 years

(Cl. D74—2)

To all whom it may concern:

Be it known that I, George Knorr, a citizen of the United States, residing at Chicago, in the county of Cook and State of Illinois, have invented a new, original, and ornamental Design for a Memorandum Card and Pencil Holder, of which the following is a specification, reference being had to the accompanying drawing, forming part thereof.

Fig. 1 is a front elevational view of a memorandum card and pencil holder showing my new design;

Fig. 2 is a rear elevational view thereof; and

Fig. 3 is an end elevational view looking from the right of Figure 1.

I claim:

The ornamental design for a memorandum card and pencil holder, as shown.

GEORGE KNORR.
